FILM-FEEDING DEVICE.

Application filed October 8, 1924, Serial No. 742,451, and in Germany January 12, 1924.

This invention relates to film feeding devices of the kind comprising a picture adjusting mechanism and resides in an improved construction and combination of parts of such devices as will be more fully understood from the following description and the accompanying drawings.

As an embodiment of the subject-matter of the invention, a moving picture projection machine is illustrated in the drawings in which:

Fig. 1 is a vertical section through the projection machine;

Fig. 2 is a section along the line 2—2 of Fig. 1, seen from the left;

Fig. 3 is a section along the line 3—3 of Fig. 1, seen from above;

Fig. 4 is a detail, partly in section, on an enlarged scale and

Fig. 5 is a detail of Fig. 3, likewise on an enlarged scale.

Referring now to the drawing, A designates the casing of the projection machine which is closed at all sides and in which is mounted the driving shaft B on which are fastened a rope pulley b^1 and a double wheel b^2, b^3 , see particularly Figs. 2 and 3. The pulley b^1 is in connection with the driving motor, not shown. The wheel b^2 is a screw wheel and meshes with another screw wheel c^1 which is carried by an upright shaft C mounted in the casing A. Through the intermediary of pairs of gear wheels $c^2 d^1, c^3 e^1$ and $c^4 f^1$ the shaft C imparts rotation to the shutter D which is mounted on the shaft d^2 , as well as to the film winding drums E and F which are mounted on the shafts e^2 and f^2 . The shafts d^2, e^2 and f^2 are mounted for rotation in the casing A. The wheel b^3 of the double wheel b^2, b^3 is constructed as a spur gear and meshes with a spur wheel G the teeth of which are much broader than those of the spur wheel b^3 and which is rigidly connected with a sleeve G¹. The sleeve G¹ is both rotatable and shiftable on a shaft H. The shaft H is mounted eccentrically in a rotary body member J which is rockable around the axis of the shaft B. It has a portion of a screw thread h^1 which is in engagement with a corresponding groove g^2 of the sleeve G¹. The sleeve G¹ is surrounded by a sleeve K which is shiftable in a cylindrical guide i^1 of the rotary body member J but held against ro-

tation by a pin i^2 which is fixed to the guide i^1 and in engagement with an axial longitudinal groove h^1 of the sleeve K. The sleeve K is provided with a helical groove k^2 which is engaged by a worm member a^1 which is rigidly fastened in the casing A. Fixed on the shaft H is the single tooth wheel h^2 . This wheel is in engagement with the Maltese cross m^1 fixed to a shaft m^2 which is arranged coaxially with the driving shaft B and carries the film feed drum M.

The above described construction of the machine is well-known. However, the machine is moreover provided with a manually actuated driving mechanism and a picture adjusting mechanism the driving shafts of which are co-axial. Rotatably mounted in the casing A is a hollow shaft N which is adapted to be coupled by means of a clutch $n^1 p^2$ with a co-axial hollow shaft P which is provided with a hand crank p^1 . The shaft N carries a spur wheel n^2 meshing with a spur wheel Q which is freely rotatable on the shaft f^2 . The spur wheel Q is connected with the bevel wheel f^1 by a friction coupling $g^1 S f^3$ which is operative only in one sense of rotation. The hollow shaft N rotatably receives a solid shaft R which carries at its free end a pinion r^1 which is in engagement with a toothed arc r^2 of the rotary body member J. The shaft R is provided at its other end with two teeth r^2 which are adapted to engage two notches r^3 of the hollow shaft P when same is correspondingly shifted.

During the normal working the following operation takes place.

The shaft B driven through the rope pulley b^1 imparts rotation by the intermediary of the spur wheel b^3 to the spur wheel G with the sleeve G¹, to the shaft H which is coupled with the sleeve G¹ by the elements $g^2 h^1$, and to the single tooth wheel h^2 . The single tooth wheel h^2 imparts intermittent motion to the Maltese cross m^1 and the feed drum M. On the other hand, the rotation of the shaft B is transmitted through the screw wheel gearing $b^2 c^1$ to the upright shaft C which drives the film winding drums E and F through the gearings $c^3 e^1, c^4 f^1, c^2 d^1$. The bevel wheel f^1 is rotated in the sense of the arrow α (Fig. 1), during which rotation the balls S bear with play against the

adjacent faces and therefore are prevented from imparting rotation to the spur wheel Q.

- If, for any reason, it should become necessary to operate the machine by means of the manually actuated driving mechanism, the hand crank p^1 is rotated clockwise when in the position according to the drawing in which it is coupled by the clutch $p^2 n^1$ with the hollow shaft N. This rotation of the hand crank p^1 is transmitted by the spur wheel n^2 to the idle spur wheel Q of the shaft f^2 in a sense to cause the wheel Q to rotate in counter-clockwise direction. During this rotation the balls S are pressed against the inner face of the bevel wheel f^1 imparting rotation to the same. The upright shaft C and the driving shaft B which is connected with the shaft C by the screw wheel gearing $c^1 b^2$, take part in the rotation of the bevel wheel f^1 so that the film feed drum M as well as the winding drums E and F and the shutter D are rotated in the manner already described above.
- If a wrong adjustment of the picture occurs during the working and it becomes necessary to alter the picture adjustment, the hollow shaft P is shifted axially in the direction of the arrow y, Figs. 3 and 5, by pulling at the hand crank p^1 so that the clutch $n^1 p^2$ is released and the clutch $p^3 r^2$ thrown in. Thereupon the hand crank p^1 and the solid shaft which is now coupled with the crank, are rotated. The rotation of the crank p^1 is transmitted by the toothed gearing $r^1 i^3$ to the rotary body member J which is rocked together with the guiding cylinder i^1 around the axis of the shaft B. This rocking movement of the rotary member J will cause the toothed wheel G to be shifted longitudinally by the cooperation of the parts $a^1 h^2$. Through the action of the thread portion h^1 the toothed wheel G is at the same time rotated with relation to the shaft H and the single tooth wheel h^2 by the same angle by which the rotary member J is being rocked. The rocking of the rotary body member J therefore causes an increased or decreased speed to be imparted to the toothed wheel G in a measure so that

the shaft H, the single tooth wheel h^2 and the shutter D rotate always at the same speed. Besides, the rocking of the member J causes a variation of the initial position of the Maltese cross m^1 , the same being varied by the angle of rocking of the member J. The film feed is thereby increased or decreased so that a whole picture will again appear in the aperture a^2 .

The subject-matter of the invention may not only be applied to projection machines but also to film copying or the like apparatus.

Claims:

1. In a film feeding device comprising a picture adjusting mechanism, a driving mechanism including a hollow driving shaft for the normal feeding of the film, a driving shaft for the picture adjusting mechanism, this shaft being arranged concentrically with relation to the first said driving shaft, and a common actuating member for both shafts.

2. In a film feeding apparatus comprising a picture adjusting mechanism including a driving shaft, a driving mechanism for the normal feeding of the film including also a driving shaft, the two driving shafts being arranged co-axially with relation to each other, and an actuating member adapted to be selectively coupled with said shafts.

3. In a film feeding apparatus comprising a picture adjusting mechanism including a driving shaft, a driving mechanism for the normal feeding of the film including also a driving shaft, the two driving shafts being arranged co-axially with relation to each other, and an actuating member for said shafts, said actuating member being mounted for rotation and adapted to be shifted axially into two coupling positions, means for coupling the actuating member in one of the said positions with one of the driving shafts and means for coupling it in the other position with the other driving shaft.

The foregoing specification signed at Essen, Germany, this 9th day of September, 1924.

JOSEPH HAPPACHER.
